F. M. BARRIER, OF STEVENSON, ALABAMA.

Letters Patent No. 73,945, dated February 4, 1868.

IMPROVEMENT IN CULTIVATORS.

The Schedule referred to in these Letters Patent and making part of the same.

TO ALL WHOM IT MAY CONCERN:

Be it known that I, F. M. BARRIER, of Stevenson, in the county of Jackson, and State of Alabama, have invented a new and improved Cultivator; and I do hereby declare that the following is a full, clear, and exact description thereof, reference being had to the accompanying drawings, making a part of this specification, in which—

Figure 1 is a perspective view of the improved cultivator.

Figure 2 is a top view of the same.

Figure 3 is a perspective view of one of the U-shaped brackets.

Similar letters of reference indicate corresponding parts in the three figures.

This invention relates to an improvement on the construction and mode of strengthening that class of cultivators, wherein three standards, each carrying a shovel, are applied to two handles or stilts and a beam, the standards being arranged at regular distances apart, and in a gang.

The nature of my invention and improvement consists in the employment of metallic U-shaped brackets as a means of setting off the two outside standards from and securing them rigidly to the cultivator-beam, as will be hereinafter described.

To enable others skilled in the art to understand my invention, I will describe its construction and operation. In the accompanying drawings—

A represents the main beam of the cultivator, which is provided with a clevis on its front end, and constructed like a common plough-beam. B B are the two handles or stilts of the implement, which are also constructed and applied to the beam A like those of a common plough. Near the rear end of the beam A, a standard, D, is secured by mortising its upper end into said beam, and employing a front inclined brace-rod, a, and on the lower end of this beam a shovel of any suitable form is secured. On each side of the standard D is a beam carrying another shovel-plate corresponding to the shovel on said standard D. The standard C is secured to the beam A by means of a bracket, E, and brace-rod, a, and the upper end of this standard C is rigidly secured to the left-hand stilt B, as shown in the drawings. The standard C', which is on the right-hand side of the beam A, is also secured to this beam by means of a bracket, E, and brace-rod, a, and at its upper end it is secured to the right-hand stilt B. The upper end of the rear standard C is secured to the inner side of its stilt B, and the upper end of the front standard C' is secured to the outer side of the right-hand stilt B, as shown. The standards C C' are set off some distance from the intermediate standard D, and firmly held in this position by the brackets E, braces a, and stilts or handles B B. The brackets E, from which the parts derive the greatest strength, are of metal, bent or cast in the U-form shown in the drawings, and secured to the sides of the beam A by means of bolts passing transversely through their bent ends and through the beam A. The standards are firmly bolted to the outer ends of these brackets, and are thereby set off some distance from each other, and rigidly supported in such positions.

The brackets not only serve as substantial braces for the standards against forward or backward strain, but they serve as offsets for spacing the standards.

I am aware that wooden blocks have been interposed between the standards of a cultivator and the beam thereof, through which there were bolts passed, which secured the standards, the beam, and the interposed blocks together. I am also aware that the beams of cultivators have been curved, with offsets upon them, against which the side standards were secured. This latter plan is preferable to the use of wooden blocks, but it necessarily involves considerable labor and expense to produce the beams with offsets formed on them. I am also aware that it is not new to secure the upper ends of the side beams of a cultivator to the handles or stilts, as this has been done before, with the wooden offsets applied between the standards and the beam.

Having described my invention, what I claim, and desire to secure by Letters Patent, is—

The construction, arrangement, and combination of the central beam A with its shovel or plough, the side beams C C', with their shovels or ploughs, the U or arched-shaped brackets E E, and braces a a, all as and for the purpose described.

F. M. BARRIER.
